(57) **CLAIM**

The ornamental design for an ergonomic walking cane, as shown and described.

DESCRIPTION

FIG. 1 is an isometric view of an ergonomic walking cane showing my new design;

FIG. 2 is a front view thereof;

FIG. 3 is a rear view thereof;

FIG. 4 is a top view thereof;

FIG. 5 is bottom view thereof;

FIG. 6 is a left side view thereof; and,

FIG. 7 is a rear view thereof.

The broken lines depict portions of the article that form no part of the claimed design.

1 Claim, 4 Drawing Sheets
